UNITED STATES PATENT OFFICE.

DUDLEY T. FISHER, OF COLUMBUS, OHIO, ASSIGNEE TO THE JEFFREY MANUFACTURING COMPANY, OF COLUMBUS, OHIO, A CORPORATION OF OHIO.

MINING-MACHINE.

1,247,386.

Specification of Letters Patent. Patented Nov. 20, 1917.

Application filed October 8, 1913. Serial No. 794,122.

To all whom it may concern:

Be it known that I, DUDLEY T. FISHER, a citizen of the United States, residing at Columbus, in the county of Franklin and 5 State of Ohio, have invented certain new and useful Improvements in Mining-Machines, of which the following is a specification, reference being had therein to the accompanying drawing.

10 The invention relates to side cutting machines and especially to machines of this class which are adapted for use in room and pillar mining.

15 The object of the invention is the provision of improved means for guiding the machine and holding it up to the work as it is fed along the face of the coal. Machines of the character in question, such as are now in common use, comprise a bed frame 20 designed to rest upon and move freely over the floor of the mine and an endless chain cutting apparatus which projects from the inner end of the bed frame and is, as an entirety, fixed in relation to said frame.

25 The bar which supports and guides the cutter chain must be relatively narrow to permit the machine to be directed upward or downward as the side cutting proceeds, and, inasmuch as it is necessary to work close to 30 the ribs or side walls of the room, it is also necessary that the bed frame be relatively narrow. Up to the time of my invention, these machines have been propelled or fed along the face of the coal by a flexible draft 35 device—cable, chain or the like—arranged to exert a forward draft on the inner part of the bed frame, and a section of cable or chain has been arranged to exert a retarding draft on the outer part of the machine 40 to counteract the reaction of the coal against the cutters and prevent the outer end of the machine from swinging forward too rapidly.

45 My invention contemplates the use of a cable or the like for propelling the machine along the face of the coal, but I effect the guidance of the machine and hold it in proper relation to the face of the coal in a manner and by means differing from those 50 heretofore employed. It has been discovered that an endless chain cutting apparatus can be prevented from working out from under the coal if it is inclined forward so that its inner end leads the outer end sufficiently. I 55 take advantage of this characteristic of the

endless chain cutting apparatus and provide the machine with a guide bar secured to the inner end of the bed frame and projecting forward therefrom along the face of the coal so as to give the machine, in effect, a bearing point against the coal face considerably in advance of the machine proper. In this way the tendency of the outer end of the machine to swing forward, due to the reaction of the coal on the cutters, is resisted 60 and this resistance to the swinging of the machine taken in connection with the tendency of the cutters to hold the machine up to the face by reason of the inclination of the cutting apparatus, results in the maintenance of the machine in proper working 65 relation to the coal face as the undercutting proceeds. Furthermore, I provide a connection between the guide bar and the bed frame adapted to readily permit movement 70 of the bar relative to the frame and even the entire removal of the bar from the frame, if that be desired; and hence it is possible to work with my machine close to the ribs 75 or side walls of the room.

80 Without limitation of my invention to any specific construction, I show in the accompanying drawings, as an illustrative embodiment of the invention, the construction which I at present deem preferable.

In the drawings,

Figure 1 is a plan view of the machine with the guide bar removed, upper parts being removed or broken away to illustrate the gearing in the lowermost parts of the 90 machine;

Fig. 2 is a left side elevation of the machine as shown in Fig. 1;

Fig. 3 is a fragmentary view showing in rear elevation a detail of the construction 95 at the outer rear corner of the bed frame;

Fig. 4 is an enlarged vertical section on the line 4—4 of Fig. 1;

Fig. 5 is a detail vertical sectional view of the clutch which connects the driving 100 gearing to the rear sprocket wheel of the cutter chain, and of the devices for actuating said clutch;

Fig. 6 is an enlarged vertical longitudinal section on the line 6—6 of Fig. 1;

Fig. 7 is an enlarged vertical longitudinal section on the line 7—7 of Fig. 1;

Fig. 8 is a diagrammatic view showing the machine at the beginning of the sumping or entering cut;

Fig. 9 is a diagrammatic view showing the machine when the sumping cut has been completed and the side cut is about to be started;

5 Fig. 10 is a diagrammatic view showing the machine at the end of the swinging movement which it is given at the beginning of the side cut, and prior to the attachment of the guide devices;

10 Fig. 11 is a diagrammatic view showing the machine with the guide devices attached preparatory to a continuation of the side cutting along the face;

15 Fig. 12 is a diagrammatic view showing the machine at the point at which the guide bar encounters the left rib;

20 Fig. 13 is a diagrammatic view showing the position taken by the machine as it advances from the position shown in Fig. 12 along the guide bar;

Fig. 14 shows the machine with the guide bar removed and the side cut completed;

25 Figs. 15, 16 and 17 are detail views of parts of the guiding apparatus detached.

30 Referring in detail to the construction shown, the bed frame is composed of a bottom plate 1, flanged side plates 2, 2 and a top plate 3 which is preferably in the form of a casting, all of which are connected to form a rigid box-like structure open at its inner and outer ends. 4 is a cutter bar or arm which projects from the inner end of the bed frame and extends outward between the top and bottom plates thereof, being 35 rigidly secured to the said frame. This cutter bar, which as to details may be constructed in any preferred manner, is formed with a longitudinal slot or opening 5, and has in its outer periphery a guide or way 40 for an endless cutter chain 6. Adjacent the outer end of the cutter bar is a sprocket wheel 7 over which the cutter chain passes and by which it is driven. The sprocket wheel 7 is loosely mounted on an upright 45 shaft 8 which has its lower end mounted on the bottom plate 1 of the bed frame and is preferably secured to the bottom plate by means of a base casting 9 riveted to said plate, the casting having an aperture in 50 which the shaft is tightly fitted, and further secured by a key 10. The shaft 8 can be given further support in the manner indicated in Fig. 5 which shows the motor—presently to be described—having its frame 55 metal formed with a socket to receive the upper end of the shaft.

The machine is designed to be propelled along the face of the coal during the cutting operation by a cable or rope, and upon 60 the inner end of the bed frame is mounted a winding drum 11. A suitable draft cable 12 has one end secured to the winding drum so that it can be wound upon the drum when the latter is turned. The cable 12 passes 65 downward from the drum and under a guide

sheave or pulley 13 which is mounted in a block 14. This pulley block is in the nature of a caster frame having a hollow or cylindrical stem or spindle mounted in the top plate of the bed frame. The arrangement is such that the cable 12 passes downward through said hollow spindle and thence under the pulley. With the pulley mounted in this manner, it will be seen that the cable 12 can be led off in any desired 70 direction within a range of about 180°. The drum 11 is mounted upon a longitudinally arranged shaft 15 carried in bearings 16 and 17 on the top plate of the bed frame.

18 is an electric motor which, as to details 80 of construction, may be of any preferred form, and which is mounted upon the outer end of the bed frame with its armature shaft arranged longitudinally of the machine. This motor is designed to drive the winding drum 11 and the cutter chain 6, and to this end the following gearing is provided. The armature shaft 19 of the motor carries at its inner end a bevel pinion 20 which meshes with a bevel gear 21 on the 90 vertical shaft 22. The lower end of this shaft is mounted in a bearing 23 formed in a depending bracket on the bed frame (see Fig. 4). The upper end of the shaft turns in a bearing 24 carried by an upstanding frame or yoke 25 mounted on the bed frame. 26 is a worm loosely mounted on the shaft 22 and operatively connected with the bevel gear 21 by means of an improved friction clutch mechanism which is designated as an 95 100 entirely by 27.

The clutch mechanism 27 comprises the following parts. 26^a is an upward extension carried by the worm 26 and forming the driven element of the clutch. The depending hub 21^a of the gear 21 constitutes the driving element of the clutch and the two elements are frictionally connected by a series of friction disks 28, one group of which are keyed at their inner edges to the 110 driving element and the other group of which are keyed at their outer peripheries to the driven element, the arrangement being that of the well known Weston clutch. 29 is a follower plate or ring by which the friction disks 28 can be pressed together and against the driven element 26^a. The bevel gear 21 is formed with a series of apertures 21^b to receive a corresponding series of compression springs 30 which have their lower 115 ends resting upon the follower plate 29 and their upper ends engaging adjustable threaded cups 31 by which the tension of the springs can be adjusted. The follower plate 29 has a depending flange 29^a formed 120 with a groove to receive pivoted slide blocks 32 mounted in the ends of a forked lever 33, this lever being pivoted at 34 on a part of the frame structure. The opposite end of the lever 33 is apertured to receive an up- 130

right rod 35 which carries abutment nuts 36 to engage the upper side of the lever 33 and a spring 37 which is interposed between the lower side of the lever and a washer 38 5 which rests upon a nut 39 on the lower end of the rod 35. The upper end of the rod 35 is pivoted to an arm 40 on a rocker shaft 41 mounted in the yoke 25. 42 is a hand lever secured to the outer end of the rocker shaft 10 41. By pressing down on the hand lever 42 the follower plate 29 can be lifted in opposition to the springs 30 to relieve the friction disks of pressure, and by lifting the hand lever 42, the spring 37 can be drawn upward 15 against the lever 33 to increase the pressure on the follower plate 29 to any desired extent.

20 A ball bearing 43 is interposed between the gear 21 and the frame yoke 25, and a similar bearing 44 is interposed between the worm 26 and the gear 21. Through these bearings the thrust of the worm and the reaction of the clutch springs are transmitted to the frame yoke.

25 The worm 26 meshes with a worm wheel 45, which is mounted upon a longitudinally disposed shaft 46. This shaft is mounted in bearings 47, 48, carried by the top plate of the bed frame. A pinion 49 is mounted 30 to turn loosely on shaft 46 adjacent the bearing 48, and upon the front end of the shaft 46 is mounted a spur pinion 50. The latter pinion has a sleeve-like hub extension 50^a which extends through the bearing 47 and 35 has a large spur gear 51 keyed to its outer end. The outer end of the hub of gear 51 is formed with a toothed clutch extension 52 and the pinion 49 also carries on its inner end a toothed clutch element 53. A grooved 40 clutch collar 54 is slidably keyed upon shaft 46, and by means of it either the pinion 49 or the gear 51 and pinion 50 can, at will, be clutched to the shaft 46. The clutch collar 54 is shifted by means of a lever arm 55 45 which is secured to the lower end of a vertical shaft 56, said shaft carrying at its upper end a transversely disposed hand lever or bar 57. The lever 57 preferably extends to both sides of the machine so that it can 50 readily be grasped by the operator when standing at either side of the machine.

55 The pinion 49 meshes with a gear wheel 58 which is mounted upon the outer end of a short shaft 59, this shaft being carried by a bearing 60 on the bed frame. 61 is a pinion secured to the inner end of the shaft 59 and meshing with the gear wheel 51. The pinion 60 meshes with a large gear 62 which is keyed to the shaft 15 upon which the winding drum 11 is mounted. 63 is a ball thrust bearing which is interposed between the pinion 49 and the bearing 48 to take any axial thrust that may result from the action of the worm and worm wheel.

65 It will be seen that by means of the gear-

ing described, the winding drum 11 can be driven at either one of two speeds from the shaft 22, which itself is directly driven by the motor. Thus, if the clutch 54 is thrown so as to make the pinion 49 fast on the shaft 46, the rotation of said shaft will be transmitted through the pinion 49 and gear 58 to the shaft 59, thence through pinion 61, gear 51, pinion 50 and gear 62 to the winding drum 11. On the other hand, if clutch 54 is thrown so as to connect gear 51 and with it pinion 50 to the shaft 46, the rotation of said shaft is then transmitted directly through the pinion 50 and gear 62 to the winding drum 11, thus rotating the latter 30 at considerably higher speed than before. With the clutch thrown as last described, it will be noted that pinion 61, gear 58 and pinion 49 turn idly.

35 The following devices are provided for driving the cutter chain. On the vertical shaft 22, and near its lower end is mounted a spur pinion 64 which meshes with a large spur gear 65 which is mounted to turn freely upon the upright shaft 8, said gear being 40 disposed directly above the cutter chain sprocket wheel 7. On the upward extending hub 65^a of the gear is slidably mounted a collar 66 which carries a plurality of depending clutch pins 67 which extend 45 through apertures in the web of the spur gear wheel 65. The upper face of the sprocket wheel 7 is provided with a series of hollow semi-cylindrical bosses 7^a, there being one to correspond with each of the clutch pins 50 67, and when the collar 66 and said pins are in their lowermost position, the pins engage the bosses 7^a so that the rotation of gear wheel 65 is transmitted to sprocket wheel 7. The collar 66 is grooved to receive 55 a band 68 to which is connected a lever arm 69 having its forward end pivotally connected at 70 to the rigid part of the bed frame structure. A link 71 is connected at its lower end to the lever arm 69, and at 60 its upper end is connected to an eccentric band 72 which fits upon an eccentric 73. Said eccentric is mounted upon a screw stud 74 which projects from the front face of the frame of motor 18, and the eccentric is provided with a pivoted handle 75 by means of which it can be turned to actuate the link 71 and raise and lower the clutch collar 66. It will be noted that the handle 75 is very 65 conveniently located to be grasped by the operator when he desires to throw the cutter chain into or out of operation.

70 I prefer to inclose the inner train of gearing by a casing 76 for obvious reasons. On one side of this casing, the top part of which 75 is broken away in Fig. 1 to disclose the gearing, I mount a rheostat 77 for the motor and an operating shaft 78 extends from the rheostat to the outer end of the bed frame where it is provided with a hand wheel 79 80

which can be conveniently grasped by the operator when at the outer end of the machine.

During the operation of undercutting, 5 when the machine is being drawn along the face of the coal by the cable 12, there is a tendency for the outer end of the machine to swing around in the direction in which the machine is moving, because ordinarily 10 the friction between the bed frame and floor of the mine is not sufficient to balance the reaction of the coal upon the cutter frame. For the purpose of controlling the angular position of the machine relative to the face 15 of the coal and of holding it up to its work, I provide the following devices: 80 is an elongated guide bar arranged across the inner end of the bed frame and detachably and adjustably connected to said frame. A 20 shoe which is slidably mounted on the bar 80 is pivoted to a bracket or lug 82 carried by the top plate of the bed frame. 83 is a tie rod pivotally connected at one end to the bar 80 and at its other end to an eye 84 carried 25 by the bed frame near the inner right hand corner thereof. 85 is a tie and brace rod pivotally connected at its inner end to the right hand end of the bar 80 and at its outer end adjustably connected to the outer right 30 hand corner of the bed frame. This latter connection is preferably made by means of a forked lug or bracket 86 carried by the bed frame of the machine and a nut 87 which is threaded on the outer end of the 35 rod 85. This nut has a rounded inner end which engages the correspondingly concaved face of the lug 86, and is shaped at its outer end to form a hand wheel which can be grasped and readily turned to adjust the 40 nut on the rod. With this construction the guide bar 80 can be adjustably secured in any desired angular relation to the machine.

At its forward end the guide bar 80 is curved outward away from the face of the 45 coal and on its extreme end is mounted a guide sheave 89 for the draft cable 12.

At various points on the bed frame of the machine I provide idler guide sheaves over which the feed cable 12 can be passed in various ways when it is desired to move the machine about over the floor of the mine by means of its own power. On the outer end of the bed frame I mount sheaves 90, 91 and 92, and on the rear or right hand side of the 55 bed frame I provide a sheave 93.

The operation of the machine will now be readily understood. The machine, on being brought into the mine room, is unloaded from the truck and brought to the face of the 60 coal near one of the ribs. Assuming that the machine is designed to cut from right to left, it would be brought to the face adjacent the right rib as shown in Fig. 8. The first operation ordinarily is the making of the sumping cut by thrusting the cutting apparatus

endwise into the coal. In doing this the machine must be guided and this can be done in various ways. The method indicated in the drawings involves the use of a jack 94 which is passed through the longitudinal slot or opening in the cutter bar with its lower end engaging the floor and its upper end engaging the roof of the mine. This jack having been set as in Fig. 8, the feed cable 12 is passed outward over the 70 guide sheaves 90, 91 and 92, and thence inward to a jack 95 to which its end is secured. The motor having been started and the cutters thrown into operation, the clutch 54 is thrown into engagement with the pinion 49, 75 thus driving the cutters and turning the winding drum 11 at slow speed. The tension on the cable 12 draws the machine inward against the coal, forcing the cutter frame under the coal as the latter is cut 80 away. The reaction of the cutters as the entering cut begins tends to throw the inner end of the cutter frame to the right, but this action is counteracted by the guiding effect of the jack 94; and the draft of the cable on 85 the outer right hand corner of the bed frame of the machine overcomes any tendency of the outer end of the machine to swing to the left.

When the machine has been advanced 95 fully into the coal, as shown in Fig. 9, the jack 94 is removed and the cable 12 extended along the face to the left rib where it is made fast to an anchor or a jack 96. A jack is then placed at 97 with its lower end bearing against the front side of the bed frame near the outer end thereof. Thereupon the machine is again started and, as the jack at 97 prevents the advance of the outer end of the machine, the winding up of the cable 12 100 causes the inner end of the machine to be swung forward. During this swinging of the machine the rate of feed is readily controlled by the machine runner by means of the friction clutch 27. When the machine 105 has in this manner been swung into a position approximating that shown in Fig. 10 with the cutter bar angled well forward, the machine is stopped and the guide bar 80 is attached in the manner indicated in Fig. 11. 110 It will be observed on referring to this figure that the guide bar 80 constitutes in effect a forward extension of the machine, giving it a bearing against the coal well in advance of the cutters. It will be noted too 115 that the guide cable is carried inside the guide sheave 89 so that the effective line of draft on the machine is brought close to the face.

The machine is now started again and the 120 undercutting proceeds. The angular advance of the cutter bar is such that the drag of the bits in the coal tends to hold the machine close up to the face and the forward extension accorded by the guide bar 80 serves 125 130

to prevent the outer end of the machine from swinging forward. If, as the cutting proceeds, the material encountered by the cutters varies in hardness, it may be desirable to vary the angle of the machine to the face of the coal somewhat, and this the machine runner can easily do by simply turning the hand wheel 88.

The narrow cutter bar 4 in one of these machines extends six or seven feet under the coal, and it so holds the chain that the active cutters follow an approximately straight line of substantially that length, and along this line the cutters bear outwardly on the coal at points inside of the face. And as they engage with the coal of the kerf wall they exert a powerful, indrawing force along all that part of the bar under the coal. When the longitudinal axis of the cutter is held at an obtuse angle inclined forward and inward, as shown in Fig. 11, the bed frame outside of the face tends to be drawn inward by the reactionary force. But the cutting element must be held rigidly in its angular position, relatively to the coal face, or it will still tend to swing backward and outward. The bar 80 is a rigid element angularly related to the cutter, and with its front end so arranged as to bear against the coal face. The connection between the bar and the cutter element being rigid, the latter cannot swing backward except as the rear part of the bar 80 swings outward. Such movement is prevented by the inner portion of the cutter element bearing against a mass of coal in its native bed. Thus the bed frame, with the parts attached, including the rigid bar extension, are held firmly in predetermined positions without requiring guide rails, posts, ropes or chains at the outer end of the bed, said end being free to move forward or back when no draft is exerted.

The undercutting proceeds in the manner described until the front end of the guide bar 80 approaches the left rib or wall of the room. At this time the feed cable 12 is disengaged from the guide sheave 89 and, as the front end of the guide bar 80 comes into engagement with the side wall as shown in Fig. 12, the machine is stopped. Then the rods 83 and 85 are detached and a jack is placed at 98 with its lower end against the outer side of the rear end of the bar 80. The machine is now started again and the undercutting proceeds, the guide bar 80 remaining stationary while the machine advances along it. During this further advance of the machine along the guide bar, the outer end of the machine gradually swings forward until a position is reached such as shown in Fig. 13. Thereupon the machine is again stopped, the guide bar 80 is removed and a jack is placed at 99 against the front outer corner of the machine. Then the machine having again been started, it is swung

forward to the position shown in Fig. 14 thus bringing the undercut close to the rib so that the width of the room is maintained.

During the undercutting the rate of feed can at all times be varied and controlled by means of the friction clutch 27 for, by simply pressing downward on the hand lever 42, the machine runner is enabled to diminish the pressure on the follower plate 29 of the clutch to any desired amount so as to correspondingly reduce the rate of feed. This is especially advantageous when the cutter bar is to be swung forward at the beginning of the side cut and again at the end of the side cut.

When the undercut is completed, the feed cable 12 can be extended to a point adjacent the truck at the right side of the room and the machine drawn over the floor of the mine by its own power and similarly loaded upon the truck in the now well known manner of handling machines of this character.

While I have set forth the particular preferred form of guide bar and the particular preferred manner of connecting it to the bed frame of the machine, it should be understood that there can be wide variation as to these matters within the scope of my invention as set forth in the following claims.

I do not claim as of my invention any of the features of construction incident to the bed frame, the motor, the gearing, or the cutting apparatus, by themselves considered, as I am aware that these are well known. But the parts more particularly characterizing my improvement are intimately correlated with these devices, and I have shown and described them in order that all matters of operation may be readily understood.

What I claim is:

1. The combination of the relatively narrow bed frame extending longitudinally outward from the coal face, the narrow cutter bar projecting inward from the inner end of said frame, the cutter chain moving around said bar, the bar and chain being adapted to be inclined forward and inward to form an elongated, inclined, rectilineal cut; an elongated, horizontally-arranged detachable abutment bar adapted to be held rigidly in relation to the cutting apparatus and bearing against the coal at points in advance of and relatively remote from the longitudinal axis of the cutting apparatus and adapted to hold said axis at an acute angle of inclination to the coal face, and a draft device for propelling the machine along the coal face, said draft device engaging with the front end of said abutment bar, and also with a stationary abutment in advance of the bar; said parts being arranged to cause the draft to be exerted along a line close to the coal face.

2. The combination of the bed frame, the

8

cutting mechanism projecting from the inner end of said frame and comprising a narrow, elongated bar and a cutter chain moving around the said bar, the cutter mechanism being adapted to be inclined forward and inward to form an elongated, inclined rectilineal cut, a detachable guiding abutment bar held rigidly, but adjustably, in relation to the cutting apparatus and 10 adapted to hold the latter at either of several acute angles of inclination to the coal face, and a draft device engaging with the front end of said abutment bar, the outer end of the bed frame being normally free 15 for movement forward or backward.

3. In a mining machine, the combination of a relatively narrow bed frame, a cutter bar projecting from the inner end of the bed frame and rigid therewith, an endless cutter 20 chain mounted on the said bar, means comprising a flexible draft device for propelling the machine, said draft device being adapted to be extended inward along the cutter bar so as to pull the machine endwise and project the cutter bar under the coal along lines close to one side wall of a mine room and also to be extended from the machine along the coal face so as to propel the machine laterally toward the other side wall of the 25 room, a guide bar having slidable connection with the bed frame and extending forward therefrom to engage the coal face, and means adapted to normally prevent a sliding movement of the guide bar relative to the bed frame and to be disengaged so as to permit such sliding movement and allow the machine to move close to the last named side wall.

4. In a mining machine, the combination 40 of a relatively narrow bed frame, a cutter bar projecting from the inner end of the bed frame and rigid therewith, an endless cutter chain mounted on the said bar, means comprising a flexible draft device for propelling the machine, said draft device being adapted to be extended inward along 45

the cutter bar so as to pull the machine endwise and project the cutter bar under the coal along lines close to one side wall of a mine room and also to be extended from the machine along the coal face so as to propel the machine laterally toward the other side wall of the room, a guide bar extending forward from the bed frame to engage the coal face, a shoe slidably engaging said bar and pivotally connected to the bed frame, means for normally preventing the guide bar from sliding relative to the shoe but adapted when disengaged to permit such movement, and means for securing the guide bar in 50 definite angular relation to the longitudinal axis of the machine.

5. In a mining machine, the combination of a relatively narrow bed frame, a cutter bar projecting from the inner end of the bed frame and rigid therewith, an endless cutter chain mounted on the said bar, means comprising a flexible draft device for propelling the machine, said draft device being adapted to be extended inward along the 55 cutter bar so as to pull the machine endwise and project the cutter bar under the coal along lines close to one side wall of a mine room and also to be extended from the machine along the coal face so as to propel the machine laterally toward the other side wall of the room, a guide bar extending forward from the bed frame to engage the coal face, a shoe slidably engaging said bar and pivotally connected to the bed frame, means 60 for normally preventing the guide bar from sliding relative to the shoe but adapted when disengaged to permit such movement, and adjustable means for securing the guide bar in 65 definite angular relation to the longitudinal axis of the machine.

In testimony whereof, I affix my signature, in presence of two witnesses.

DUDLEY T. FISHER.
